UNITED STATES PATENT OFFICE.

SAM B. FLINT, OF MARSHFIELD, OREGON.

DEVICE FOR AND PROCESS OF DRYING AND OILING SHOES.

Application filed May 14, 1924. Serial No. 713,236.

To all whom it may concern:

Be it known that I, SAM B. FLINT, a citizen of the United States, residing at Marshfield, in the county of Coos and State 5 of Oregon, have invented certain new and useful Improvements in Devices for and Processes of Drying and Oiling Shoes, of which the following is a specification.

This invention relates to a device for and 10 process of drying and oiling shoes, and has as an object the provision of means whereby heat may be applied to the interior of a shoe and oil may be simultaneously applied to the interior surface thereof where- 15 by the water is caused to leave the leather by evaporation and the oil is drawn in by capillary attraction at the same time.

A further object of the invention is the 20 provision of a device for maintaining a shoe in a distended condition while being dried and oiled.

A further object of the invention is the 25 provision of a process for rendering oil limp by means of heat and of introducing the oil into the pores of the leather by capillary attraction at the same time that water is being driven out from the same leather.

Further objects will appear from the following description when read in connection 30 with the accompanying drawings showing the device embodied for carrying out the process; and in which—

Figure 1 is a central vertical section of a shoe with the device in place; and

Fig. 2 is a like section on a larger scale showing the filling nozzle and plug.

As shown, the device comprises the receptacle 10 of the nature of a hot water bottle formed of water proof flexible material as rubber, and of a shape to substantially fit the interior of the shoe to be treated. To introduce water or other heated liquid into the interior of the device, there is shown the filling nozzle 11 interiorly screw threaded for the reception of a screw plug 12. To hang a shoe with the device in place while the shoe is being treated a ring 13 may be attached to the plug 12.

To hold oil upon the surface of the device 50 in contact with the inner surface of the shoe 14, a covering of material 15 is provided which may be formed of canvas or other suitable material. To prevent oil from soaking into the covering 15, the surface thereof is treated with an impervious substance 55 16. A suitable covering is in prac-

tice found to be shellac although other varnishes or coatings which are sufficiently flexible and impervious to oil and water may be utilized.

In the use of the device and to carry out the process of the invention the empty bottle 10 is introduced into the shoe. Before introduction of the bottle into the shoe its outer surface is smeared with oil which it 65 is desired to introduce into the leather. The bottle is then filled with hot water and the shoe hung up or set away.

It is found that the heat dries out the 70 moisture in the leather and the oil rendered more fluid by the heat, and will be drawn into the leather by capillary attraction. It is further found that the oil will be introduced into the leather more readily 75 when moisture is present to be driven out than would be the case if the shoe were dry when the device was introduced therein.

The facility with which water in the 80 leather in shoes may be replaced by oil by means of the process of the invention is unexpected and surprising. The device is of great advantage to men such as lumbermen whose shoes become thoroughly soaked while about their day's work, and where it is desired to have the water removed from the 85 shoes over night and to have the shoes warm and pliable and ready for use in the morning, such result being accomplished with great facility and effectiveness.

Minor changes may be made in the physical embodiment of the invention and in the 90 steps of the process within the scope of the appended claims, without departing from the spirit of the invention.

I claim:

1. A device for drying and oiling shoes comprising in combination a flexible receptacle adapted to approximately fit the interior of a shoe, a flexible oil-proof cover covering for said receptacle adapted to 100 carry a coating of oil, said receptacle and cover adapted to be introduced unfilled into a shoe and to be filled with heated liquid in the shoe.

2. The process of drying and oiling water-soaked shoes comprising applying oil to the outer surface of a flexible receptacle approximately fitting the interior of the shoe, introducing the empty oiled receptacle into the shoe, filling the receptacle with heated 110 liquid to distend the same into close contact with all portions of the shoe thereby to ren-

der the oil liquid and simultaneously introduce the heated oil into the material of the shoe and dry the moisture therefrom.

3. The process of drying and oiling water-soaked shoes comprising applying oil to the outer surface of a receptacle adapted to approximately fit the interior of the shoe and provide a shape-sustaining form therefor, and subjecting the shoe and oil to heat imparted by a medium within the receptacle

to render the oil liquid and simultaneously introduce the heated oil into the material of the shoe and dry the moisture therefrom.

In testimony whereof I affix my signature in the presence of two witnesses.

SAM B. FLINT.

Witnesses:
